HANDLE

William Menezes, Peabody, and Gregory F. Fossella,
Boston, Mass., assignors to National Radio Company,
Inc., Melrose, Mass., a corporation of Delaware

Continuation of design applications Ser. No. 78,920 and
Ser. No. 78,923, Mar. 9, 1964. This application Oct. 5,
1964, Ser. No. 82,234

Term of patent 14 years

(Cl. D10—8)

FIG. 1

FIG. 2

FIG. 3

FIG. 4

FIG. 5

FIG. 6

FIG. 1 is a view in top perspective of a handle showing the preferred embodiment of our new design;

FIG. 2 is a view in side elevation of the handle of FIG. 1;

FIG. 3 is a section taken along the line 3—3 of FIG. 2;

FIG. 4 is a view in top perspective of a handle showing another embodiment of our new design;

FIG. 5 is a view in side elevation of the handle of FIG. 4; and

FIG. 6 is a section taken along the line 3—3 of FIG. 5.

This application is a continuation of applications D. 78,920 and D. 78,923, both filed March 9, 1964.

We claim:

The ornamental design for a handle, as shown and described.
